ENDLESS CONVEYER

Filed May 28, 1924

UNITED STATES PATENT OFFICE.

HENRY D. HAMPER, OF AURORA, ILLINOIS, ASSIGNOR TO WESTERN WHEELED SCRAPER COMPANY, OF AURORA, ILLINOIS, A CORPORATION OF ILLINOIS.

ENDLESS CONVEYER.

Application filed May 28, 1924. Serial No. 716,427.

This invention relates to improvements in endless conveyers primarily intended for use in connection with elevating grading machines. In such machines the elevator that 5 extends laterally from the wheeled frame of the grading machine is usually of considerable length so as to carry the dirt that is deposited on it in the usual manner to the proper distance to discharge it over the upper 10 end of the elevator into a wagon or other vehicle standing at a distance from the side of the machine. Various mechanisms are provided on the machine for varying the inclination of the elevator, and in order not to have to adjust 15 just the entire elevator each time that it is desired to vary the height of the discharge end of the elevator it has been common to construct such elevator of two aligned sections hinged together so that the outer section 20 alone could be moved vertically to secure the desired height of the discharging end. Such jointing or hinging together of the two sections in former constructions has, however, been objectionable in that by reason of wear 25 or slight imperfection of fit of the hinge members the axes of the sprockets carried by the two sections and over which the drive chain runs, and also the axes of the drums or rollers at the ends of the elevator frame, would not be 30 in perfect parallelism, as of course is necessary for perfect driving and smooth, easy movement of the endless conveyer that runs over such drums or rollers. It is the object 35 of my invention to provide improved means for so connecting the two sections of such an elevating apparatus together that they can be brought into perfect lateral alignment and so maintained, and thus, because of the resulting parallelism of the axes of the driving 40 sprockets and of the drums or rollers that the belt runs over, ensure the desired smooth and accurate movement of the belt.

In the drawings,—

Fig. 1 is a side elevation of inner end portions of the two sections of a grading machine elevator, said sections being connected together by means embodying the invention;

Fig. 2 is a view partly in plan and partly in horizontal section illustrating the improved connection of the elevator sections, some of the elevator parts being partly broken away; and

Fig. 3 is a vertical cross-section taken substantially on the line 3—3 of Fig. 1.

55 Referring to the several figures of the draw-

ings,—10 and 10^a indicate the side members of the inner and outer sections of the elevator frame of a grading machine, which sections are hinged together for relative vertical swinging, and, as hereinafter particularly described, are so connected that at all times the corresponding side members of both sections may be maintained in the same vertical plane, whereby the axes of the sprockets of the driving mechanism, and the axes of the rollers 60 over which the conveyer belt runs will always be parallel—it being understood that one of the sprocket wheels will be mounted upon one of said sections and the other sprocket wheel on the other of said sections, and that the two 65 drums or rollers over which the belt runs will be respectively near the inner end of the inner section and the outer end of the outer section. The sprocket wheel and chain driving mechanism is not shown, since, as its arrangement in machines of the character referred to is well understood, such showing is not deemed necessary. A portion of the endless conveyer belt is shown and indicated by 70 11. Secured to the side members 10, 10^a of 75 each elevator frame section are a plurality of brackets 12, one of which is shown in connection with each section, which brackets project above the upper margins of the members 10, 10^a and overhang the belt 11, as shown in 80 Fig. 3, and to such brackets are secured side boards 13 whose lower edges are close to said belt, so that such side boards form means for retaining on the belt the dirt that the belt is carrying for delivery from the lower to the 85 upper end thereof. 14 indicates rollers journaled at intervals on the elevator frame and acting as intermediate supports for the belt 11, as usual. The side boards 13 are preferably formed of channel iron, as clearly 90 shown in Fig. 3, and the adjacent ends of said side boards are offset and overlap, as shown in Fig. 2, so that, together with the belt, a continuous unbroken passage is formed 95 from one end of the elevator to the other. As shown in Figs. 1 and 2, the flanges of the side boards 13 are cut away adjacent to their adjoining ends sufficiently to permit of 100 vertical movement of one section relatively to the other when the outer section of the elevator, which is the one the side members of which are here indicated by 10^a, is independently moved to raise or lower its upper or 105 discharge end.

The two elevator frame sections are hinged— 110

ly secured together by similar devices secured at opposite sides of the elevator, as clearly shown in Fig. 2. As shown, each of the two side members of one of the frame sections—those numbered 10 in the construction shown—has bolted to it a stationary hinge member 15 in the form of a bar having a yoke-shaped head 16, which head projects beyond the outer end of the side member to 5 which it is secured. The cooperating hinge members 17 are connected with the side members 10^a of the outer frame section and each is in the form of a stem, preferably angular in cross-section, as shown in Fig. 3, having a 10 yoke-shaped head 18 similar to the other head 16, and a screw-threaded shank 19 that, as clearly shown in Fig. 2, is offset relatively to the stem so as to lie at a distance from and substantially parallel with the side member 15 of the elevator frame with which it is connected. The hinge members 17 are not bolted or immovably fixed in place as are the hinge members 15, but the stem of each hinge member 17 is slidingly supported against a side 20 member 10^a of the elevator frame by guide means in the form of a hood or casing 20 that is shaped to approximately conform to the shape of the stem, such hood or casing being secured to the side member 10^a by bolts 21, as 25 best shown in Fig. 3. Preferably this hood or casing will be ribbed as at 22 for strengthening purposes. The offset screw-threaded shank 19 of each hinge member 17 passes loosely through an eye in an abutment or bracket 23 that is bolted to the face of the adjacent side member 10^a and upon opposite sides of this eye are nuts 24 that are screwed upon the shank 19. 25 indicates a pintle that passes through the two interlapping yoke-shaped heads 16 and 18 of each pair of hinge members for the purpose of pivotally connecting them together.

It will be evident that with the two sections of an elevator frame hingedly connected together in the manner described, the outer or upper section of the elevator frame can be swung up or down to raise or lower its discharge end as may be required to suit varying conditions, and if for any reason the connection of the two sections is such that the outer section becomes slightly deflected laterally so that the axis of the sprocket wheel, and the drum or roller that it carries, is not in perfect parallelism with the similar parts carried by the other section, such deviation from parallelism can be very easily remedied, as all that need be done is to loosen the nuts 24, and then, after swinging the outer section laterally to bring it into lateral alinement with the other section, said nuts can again be tightened up against their respective eyes 23 to hold it in position. The slight lateral shifting necessary to produce this correct alinement can be accomplished by loosening the proper one of 55 each of the pairs of nuts 24 and then screwing

up the other nuts of such pairs so that when the two sections are properly alined the apertured ear portion of each bracket 23 will be firmly clamped between the nuts. The holes in the brackets through which the shanks 19 70 pass are of sufficiently greater diameter than such shanks to permit this sidewise adjustment to be readily made, and during such adjustment the stems of the hinge members 17 slide easily in the guides formed by the hoods 75 20 and the adjacent outer faces of the frame members 10^a to which such hoods are secured.

By my invention perfect alinement of the two sections is always easily attainable, and consequently the sprockets that are carried 80 respectively by the two elevator frame sections may be kept in proper alinement so that excessive wear on the chain and sprockets will be prevented and the belt caused to run smoothly and evenly.

What I claim as my invention and desire to secure by Letters Patent, is—

1. An elevator for elevating graders comprising adjoining inner and outer frame sections, an endless belt supported by said sections, hinge members connecting said sections together for relative vertical swinging, guide means for one of said hinge members permitting longitudinal shifting motion of said hinge member relative to the section on which it is mounted but preventing swinging motion thereof relative to said section, and screw threaded adjusting means for effecting longitudinal shifting motion of said latter hinge member, whereby said inner and outer frame sections can be relatively adjusted laterally with reference to the run of the belt.

2. An elevator for elevating graders comprising adjoining inner and outer frame sections, an endless belt supported by said sections, hinge members secured to the side portions of said sections and connecting said sections together for relative vertical swinging, one of said hinge members being adjustable relative to the section on which it is mounted, guide means for confining the adjusting motion of said hinge member to a rectilinear movement substantially longitudinally of said section, and a pair of threaded members cooperating with said latter hinge member and through which the adjustment thereof is effected, said threaded members serving positively to move said hinge member in either direction in the adjustment of the latter.

3. An elevator for elevating graders comprising adjoining inner and outer frame sections, an endless belt supported by said sections, hinge members secured to the side portions of said sections and connecting said sections together for relative vertical swinging, one of said hinge members being adjustable longitudinally of the section on which it is mounted and having a screw threaded shank, an eye carried by the latter section,

through which eye said shank extends, and nuts screwed on said shank at opposite sides of said eye for adjusting said hinge member longitudinally.

5. 4. An elevator for elevating graders comprising inner and outer frame sections, an endless belt supported by said sections, cooperating pairs of hinge members secured to the side portions of said sections and connecting 10 said sections together for relative vertical swinging, the connected ends of cooperating hinge members having yoke shaped heads interlapping one within the other, pintles passing through apertures in said yoke shaped 15 heads, one of said hinge members being adjustable longitudinally of the section on which it is mounted and having a screw threaded shank, abutment means on said latter section cooperating with said shank, and nuts screwing 20 on said shank and adapted to bear against

said abutment for adjusting said hinge member longitudinally and for securing the same in adjusted position.

5. An elevator for elevating graders comprising inner and outer frame sections hinged together for relative vertical swinging, said sections having side members, hinged members mounted on the adjacent end portions of said side members, hoods secured to the side members of one of said sections, the hinge 25 members mounted on the latter side members being slidably supported by said hoods for movement longitudinally of said side members and having screw threaded shanks, eyes carried by the latter side members through which 30 said shanks extend, and nuts screwed on said shanks for adjusting said hinge members longitudinally to maintain alinement of said inner and outer frame sections. 35

HENRY D. HAMPER.
